George D. Richards
ATTORNEY

UNITED STATES PATENT OFFICE

HARRY H. WILSON, OF NEWARK, NEW JERSEY

SQUARE GOLF GAME

Application filed August 8, 1930. Serial No. 473,829.

This invention relates, generally, to games or amusement devices, and the invention has reference, more particularly, to a novel game having features simulating those of golf.

5 The principal object of the present invention is to provide a novel game having a playing field patterned after a miniature golf course laid out in square form, and having suitable hazards, the said game employing a 10 ball adapted while playing the game to be rolled over the course, as by tilting the game, with the object of avoiding the hazards and yet causing the ball to drop successively into consecutive holes or cups provided along the 15 course.

Another object of the present invention lies in the provision of a novel game of the above character, having a playing field provided with a surface calculated to offer some resistance to the movement of the ball there- 20 over, thus enabling the player of the game to exercise more or less control of the ball in its movement so as to direct the same as desired.

25 Still another object of the present invention is to provide a novel game of the above character which is of simple, cheap construction and has a substantially flat playing field with simply constructed hazards.

30 Other objects of this invention, not at this time more particularly enumerated, will be clearly understood from the following detailed description of the same.

The invention is clearly illustrated in the 35 accompanying drawing, in which:

Fig. 1 is a plan view of the novel square golf game of this invention.

Fig. 2 is a sectional view taken along line 2-2 of Fig. 1, looking in the direction of the 40 arrows.

Fig. 3 is a perspective view of the structure illustrated in Fig. 1; and

45 Fig. 4 illustrates a fragmentary sectional perspective view, in which the playing field is provided with a roughened surface simulating grass.

Similar characters of reference are employed in all of the above described views, to indicate corresponding parts.

50 Referring now to said drawing, the refer-

ence numeral 1 designates the novel square golf game as a whole. Game 1 comprises a substantially square casing having a bottom 2 and side walls 3 extending upwardly therefrom. The upper edge portions of side walls 55 3 are bent inwardly to provide retaining flanges 4 for retaining or holding a transparent cover 5 of glass or other suitable material within the casing. Retaining flanges 4 engage the peripheral edges of the 60 outer surface of the transparent cover 5, while a spacing member 6 of suitable material, such as metal, cardboard, engages and supports the peripheral edges of the inner surface of the transparent cover 5. 65

Spacing member 6 is illustrated as formed from sheet material such as metal and lies adjacent the inner surfaces of the walls 3. Spacing member 6 rests upon the marginal edges of a playing field 7. Playing field 7 70 constitutes the upper surface of a body 8 of any desired material capable of being formed or constructed to provide the desired surface contours of the playing field. The body 8 may be made of plaster Paris or other suitable material which may be worked in a plastic state and then caused to harden, or the same may be made of wood, metal or other suitable substance. 75

The major area of the playing field 7 is substantially flat and extends parallel to the casing bottom 2. This playing field is provided with a plurality of holes or cups 9 which are suitably arranged around the playing field, preferably as illustrated in the drawing, and are numbered 1 to 6 inclusive to indicate the successive order in which said holes are to be played. Playing field 7 is illustrated as provided with hazards in the form of a centrally disposed relatively large depression simulating a lake 11, and bunkers 12 so arranged relative to the sides of the lake 11 as to compel the player to force the ball between the same and the lake margins during play. The bunkers 12 extend from the spacing member 6 inwardly toward the lake 11 but terminate short of the marginal edges of this lake to provide suitable playing spaces adjacent the lake for the passage of balls. 95

It will be noted that holes 9 marked on the 100

field as 1 to 3 are located on one side of the lake 11 and bunkers 12, whereas the remaining holes 3 to 6 are located on the opposite side of the lake 11 and bunkers 12, thereby necessitating the passage of the ball between the lake and bunkers during the playing of the game.

The surface of the playing field 7 may be suitably decorated in any manner desired as 10 by printing, painting, lithographing or otherwise depicting thereon, pictures such as 13 to 18 shown in the drawing. It will be noted that a line or other marking extends from hole 1 to hole 2, and from thence on 15 by way of the successive holes back to hole 1, thereby indicating the general course to be taken by the ball in playing the game.

The ball 19 used to play the game is preferably made of dense, hard material, such as 20 steel, and is preferably solid. The co-efficient of friction of the material of the ball 19 upon the surface of the field, should, preferably, be relatively high, so that the ball will not tend to over travel desired movements 25 and so that its movements can be controlled within reasonable limits. If desired, the surface of the playing field 7 may be roughened somewhat as by covering the playing surface of body 8 with an adhering material simulating 30 miniature grass, such as green tinted paper pulp 20, illustrated in Fig. 4. The use of such a friction material even further increases the co-efficient friction between the ball 19 and the playing field surface, so that 35 the movements of the ball can be more accurately controlled.

The preferred manner of playing the game is to use hole or cup 9 which is designated by the marking 6 on the playing field, as the 40 driving tee. From the cup marked 6 on the playing field, the ball must be rolled to the cup 9 which is marked 1 on the playing field, and from there to the cup which is marked 2 and so on to the consecutive holes until the 45 ball again returns to the cup marked 6 on the playing field. At no time should the ball roll into the lake 11. In the event that the ball does roll into the lake at any time, the same must be returned to the cup marked 6 and 50 a new start made.

It will be apparent that the nature, number and position of the hazards as well as the number of holes may be variously altered, as desired, without departing from the spirit 55 or scope of this invention. Also the relative roughness of the playing field 7 may be greatly varied, thereby obtaining varying degrees of control over the ball 19.

As many changes could be made in the 60 above construction and many apparently widely different embodiments of this invention could be made without departing from the scope thereof, it is intended that all matter contained in the above description or 65 shown in the accompanying drawing shall

be interpreted as illustrative and not in a limiting sense.

What is claimed is:

1. A square golf game comprising, a body having an upper surface which is substantially flat and square in shape, said upper surface providing a playing field having a plurality of shallow holes or cups disposed therein in spaced relation from one another, a vertical casing extending around the margins of said playing field to thereby positively limit the area of play to said playing field, said playing field having a relatively large recess in the central portion thereof providing a hazard of the general form of a lake, barrier projections extending from said vertical casing toward said lake, said barrier projections terminating short of the marginal edges of said lake to thereby provide limited play areas adjacent the margin of said lake in the proximity of said barriers, and a ball movable over said playing field for successive engagement in said holes or cups, it being necessary in playing the game to roll the ball over said limited play areas without having the ball drop into the lake or strike a barrier projection.

2. A square golf game comprising, a body with a substantially flat upper surface providing a playing field, said playing field being square in shape and having a central relatively large recess therein providing a lake hazard, a vertical casing extending around the sides of said playing field for limiting the area of play to said square playing field, barrier projections extending from opposite sides of said casing inwardly toward said lake, said barrier projections terminating short of said lake, thereby providing relatively narrow play areas lying between the inner ends of said barrier projections and the margin of said lake, said playing field having a plurality of consecutively arranged holes or shallow depressions therein, and a ball movable over said playing field for successive engagement in said consecutive holes, some of said holes being located on one side of said lake and barrier projections and the remainder of said holes being located on the opposite side of said lake and barrier projections, whereby in playing the game it is necessary to roll the ball over said narrow play areas lying between said barrier projections and said lake.

3. A square golf game comprising, a body with a substantially flat upper surface providing a playing field, said playing field being square in shape and having a central relatively large recess therein providing a lake hazard, a vertical casing extending around the sides of said playing field for limiting the area of play to said square playing field, barrier projections extending from opposite sides of said casing inwardly toward said lake, said barrier projections terminating short of

said lake, thereby providing relatively narrow play areas lying between the inner ends of said barrier projections and the margin of said lake, said playing field having a plurality of consecutively arranged holes or shallow depressions therein, said playing field being provided with lines connecting said consecutively arranged holes in series, and a ball movable over said playing field for successive engagement in said consecutive holes, some of said holes being located on one side of said lake and barrier projections and the remainder of said holes being located on the opposite side of said lake and barrier projections, said lines connecting consecutive holes on opposite sides of said lake and barrier projections being curved, whereby in playing the game it is necessary to roll the ball along a curved line and over said narrow play areas lying between said barrier projections and said lake.

In testimony, that I claim the invention set forth above I have hereunto set my hand this 7th day of August, 1930.

HARRY H. WILSON.
